UNITED STATES PATENT OFFICE.

PERCY E. HUNTER, OF PITTSBURGH, PENNSYLVANIA.

ANNEALING-BOX.

1,154,400.

Specification of Letters Patent. Patented Sept. 21, 1915.

Application filed June 18, 1915. Serial No. 34,829.

To all whom it may concern:

Be it known that I, PERCY E. HUNTER, a citizen of the United States, residing at Pittsburgh, in the county of Allegheny and State of Pennsylvania, have invented certain new and useful Improvements in Annealing-Boxes, of which the following is a specification.

My invention consists of an improvement in annealing boxes adapted for the usual uses of such devices, and it has for its object to provide means for maintaining the shape of the box by an internal supporting frame and adapting it to resist the deteriorating effects of heat and use.

Owing to the unequal expansion and contraction of the outer shell and inner supporting framework, because of differences between external and internal heat, I have found that it is desirable to so combine them as to permit the shell, or portions of it, to move away from or toward the support, within the limitations of practical working conditions. I have therefore so arranged these portions of the entire box to provide for such conditions and at all times maintain an internal support which will continuously conform to the interior shape of the shell, but in loose relation thereto.

Generally stated, the improvement consists in providing a supporting framework, so incorporated with the box as to become a part thereof, and having an upper top supporting portion, fitting underneath the box top, but not connected with it in such a manner as to rigidly control it, whereby to allow for ample range of expansion and contraction, and for ultimate regularity of shape.

Referring to the drawings, which show preferred forms of the invention, Figure 1 is a view of my improved box in vertical section, partly in elevation. Fig. 2 is a cross section on the line II. II. of Fig. 1. Fig. 3 is a view similar to Fig. 1, showing a modified construction. Fig. 4 is a cross section on the line IV. IV. of Fig. 3. Fig. 5 is a sectional detail view showing the loose connection between the overhanging end of the frame member and the top.

Referring to the construction of Figs. 1 and 2, the sides 2, 2, arched top 3 and ends 4, 4, are preferably formed integrally by suitable welding operations, preferably reinforced at the corners 5, and of customary conventional or standard form. Reinfor-

ing members, as angles 6, are riveted across the ends, and lifting eyes or hooks 7 are secured to the top at suitable locations, to facilitate handling. Longitudinal base reinforcements 8, of angle or other suitable form, extend along the bottom of each side 2, whereby to stiffen the box and provide good bearing portions. Secured to said angles 8 and to the sides at their bottoms, by riveting or otherwise, are a plurality of up-standing supports 9, which may be conveniently formed of pairs of angles with one of their flanges slightly spaced inwardly from the inner face of the box walls 70 and tops, the other flange extending inwardly and effectually bracing the supports. These frames are continued around underneath the top, as shown, following the curvature thereof, and are sufficiently close to 75 provide ample supporting strength. Between and riveted to the angles 9, if desired, are provided stiffening cross plates 9', of any desired depth. Extending across the top portions of said frames is an arched 80 plate 10 which is riveted to the flanges of angles 9 at various points, and which is thus a portion of the supporting frame. Plate 10 is sufficiently wide to engage underneath the main top portion of the box, and 85 is substantially coextensive with the length thereof inside. The terminal ends of plate 10 are loosely bolted or riveted, as at 11, to the end portions of the box top, with sufficient clearance, (Fig. 1) and a slight clearance is preferably left between the outer arched top of plate 10 and the inner arched top 3 of the box. By this construction, I provide an internal support for the top for practically its entire length, the ends of the 90 top supporting plate being loosely connected with the box top to prevent sagging, while ample opportunity is provided at all times for free expansion or contraction of the outer box shell, which is subjected to the 95 greatest heat, preferably independent of any rigid connection with the supporting framework and its top curved plate. If desired, the frame and shell may be connected, loosely at the end portions of the supporting plate as shown, or if preferred, at infrequent intervals, so as not to prevent the desirable relative expansion and contraction of the shell.

The construction of Figs. 3 and 4 is similar in the main to that just described, the parts being referred to by similar numerals

having the exponent "a." In place of the continuous arched plate 10, however, I use a series of longitudinal structural members, as angles 10^a riveted to the frame members 9^a with the flanges confronting the inner curved face of the top, the companion angles extending inwardly and being cut out for clearance, as at 10^b. The ends of the supporting angles 10^a are loosely connected with the top, as at 11^a, in the same manner as above described.

The construction, operation, advantages and utility of the invention will be readily understood by those accustomed to the use 15 of annealing boxes. It is comparatively simple, cheap, and durable, and provides ample compensations for the usual strains and requirements of devices of this type.

- What I claim is:
- 20 1. An annealing box having an inner top-supporting frame secured to the inner bottom portions of the sides and extending across and along underneath the top, and spaced inwardly thereof.
  - 25 2. An annealing box having an inner top-supporting frame secured to the inner bottom portions of the sides and extending across and along underneath the top, spaced inwardly thereof and adapted to allow expansion and contraction of portions of the shell.
  - 30 3. An annealing box having a top-supporting frame secured to the inner bottom portions of the sides and extending across and along underneath the top with an intervening space but unconnected therewith.
  - 35 4. In combination with an annealing box

having ends, sides, and an arched top; inner framing members secured to the inner bottom portions of the sides extending continuously across underneath the top, and provided with a longitudinal top-supporting member.

5. In combination with an annealing box having ends, sides, and an arched top; inner framing members secured to the inner bottom portions of the sides extending continuously across underneath the top, and provided with a longitudinal top-supporting member secured to the top at its ends.

6. In combination with an annealing box having ends, sides, and an arched top; inner framing members secured to the inner bottom portions of the sides extending continuously across underneath the top, and provided with a longitudinal top-supporting member lying adjacent the inner surface of the top but unconnected therewith whereby to provide for relative movement of said parts.

7. In combination with an annealing box having ends, sides, and an arched top; inner framing members secured to the inner bottom portions of the sides extending continuously across underneath the top, and provided with a series of longitudinal top-supporting members.

In testimony whereof I hereunto affix my signature in the presence of two witnesses.

PERCY E. HUNTER.
